FIG. 1

FIG. 2

FIG. 3

FIG. 4

FIG. 5

FIG. 1 is a front perspective view of a document roll input unit showing my new design.

FIG. 2 is a front elevational view thereof.

FIG. 3 is a rear elevational view thereof.

FIG. 4 is a top plan view thereof.

FIG. 5 is an elevational view taken from the right side thereof the left side being a mirror image of the right side.

The essential features of my design reside in the portions shown in full lines, it being understood that the broken line representation of a roll of paper shown in FIG. 1 is for purposes of illustration only.

I claim:

The ornamental design for a document roll input unit, as shown and described.
